(57) **CLAIM**

The ornamental design for a support undergarment, as shown and described.

DESCRIPTION

FIG. 1 is a perspective view of a support undergarment, showing our new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof;

FIG. 7 is a bottom plan view thereof; and,

FIG. 8 is a perspective view showing the front flaps in the open position.

The broken lines shown in the figures are for the purpose of illustrating portions of the support undergarment that form no part of the claimed design.

1 Claim, 8 Drawing Sheets
